Patented Oct. 25, 1921.

Ernest Norbert Kennedy, Inventor
by Frank P. Wentworth
his Attorney.

UNITED STATES PATENT OFFICE.

ERNEST NORBERT KENNEDY, OF BIRCHWOOD, SUNNINGDALE, ENGLAND.

RAZOR-BLADE HOLDER.

1,394,909.

Specification of Letters Patent.

Patented Oct. 25, 1921.

Application filed January 26, 1920. Serial No. 354,049.

To all whom it may concern:

Be it known that I, ERNEST NORBERT KENNEDY, a subject of the King of Great Britain and Ireland, residing at Birchwood, Sunningdale, in the county of Berks, England, have invented a new and useful Razor-Blade Holder, of which the following is a specification.

10 My invention relates to a device for enabling safety razor blades to be used for various other purposes besides shaving, and has for its objects to provide a holder for such blades which, when in its closed position, can be conveniently carried in the pocket in 15 the manner of an ordinary penknife, which will accommodate any ordinary safety razor blade at present on the market and will enable such blade when it gets too blunt to be comfortably used for shaving, to be employed either as an ordinary knife or for 20 special purposes where a comparatively keen edge is required, as for example cutting corns, trimming nails, peeling potatoes, and even as a cigar cutter.

25 Other objects comprise the provision of a device which can be used as a holder for stropping either single or double edge safety razor blades and which in an emergency may even be used as an ordinary safety razor, it 30 being possible to clean and strop the blade without removing it from the holder.

With the above objects in view I construct a holder in accordance with the invention in two parts connected together by a hinged 35 joint so that the said parts can be opened fully and closed in the same manner as the blade and holder of an ordinary penknife. One of the parts forms the handle while the other is provided with a wedge-shaped slot 40 adapted to receive an ordinary safety razor blade, means being provided for keeping the blade rigidly in position in the holder. The handle is serrated or provided with teeth along one of its edges in order to provide the 45 usual guard when the device is used for shaving purposes.

The invention further comprises other details of construction which will be herein-after described with reference to the accompanying drawing in which Figure 1 is a side view in elevation showing the device in its closed position; Fig. 2 is a detail view to a larger scale showing the wedge-shaped slot in the holder; Fig. 3 is a similar view to

Fig. 1 showing the device in its open position; and Fig. 4 is a plan view of Fig. 3 viewed from below.

Similar letters of reference relate to like parts in all the figures of the drawing.

Referring to the drawing, *a* is the handle hinged to the holder proper *b* at *c*. As shown, I prefer to form the handle *a* of two flat strips of metal *d* and *e* riveted together at their ends in such a manner as to leave a space in between to accommodate a blade *f* when the holder is in the closed position. The upper edge of the strip *e* is cut away as shown at *g* to expose the teeth or serrations *h* formed in the adjacent edge of the strip *d*. The holder *b* is also preferably formed of two thin strips of sheet metal which are so shaped that when joined together at their ends they leave between them a wedge-shaped slot *i* in which an ordinary safety razor blade *f* may be clamped by means of the set screw *j*, or as an alternative other known suitable means may be employed. The bottom edge of the holder *b*, is provided with a semi-circular recess or slot *k* and the handle *a* with a circular hole *m* for the purpose hereinafter described. Along the top edge of the holder *b* the wedge-shaped slot *i* is closed at one end thereof, as shown at *l*, in Figs. 2, 3 and 4, thus forming a shoulder against which the blade bears when it is clamped in the slot by means of the set screw *j*. Owing to this arrangement any type of blade may be used in the holder without alteration of the fittings.

The various methods of using the device as hereinbefore referred to will be obvious from the foregoing description.

In the open position it may be used as an ordinary penknife the blade being clamped in the slot and the top edge bearing against the shoulder *l* (Fig. 3). As shown more particularly in Fig. 4 the outer surfaces of the holder *b* are flat and free from any projections which might cause inconvenience when the device is thus used.

Used as a safety corn-parer or cutter, for example, the screw *j* is adjusted so as to release the pressure on the blade *f* and the blade *f* moved until its edge is flush with the edge of the holder *b*. The corn should be cut by the portion of the blade *f* left exposed by the semi-circular slot *k* on the edge of the holder. This effectively acts as a

safety device as a deep cut is thereby avoided and it is hardly possible to do otherwise than to shave or pare the corn.

When used as a cigar cutter and the cigar 5 end is placed in the circular hole *m* in the handle *a* and the device held in the open position in the right hand with the thumb under the handle *a* and the first finger at the top of the holder *b*, the finger and thumb 10 are then pressed together thus cutting off the end of the cigar.

For cutting out patterns, cutting furs, paper and the like the device is preferably used in the closed position an additional set 15 screw *q* being employed to more firmly hold the blade *f* which may be adjusted either to protrude through the handle *a* along its whole length or so that one corner only is used as a cutting point the cheeks *s* forming 20 a bearing surface facilitating the production of a straight cut.

For stropping the ordinary double edge safety razor blades, the blades must be inserted so that the edges protrude equally 25 each side of the holder.

Various other means of using the device for employing safety razor blades may be readily devised besides those described. The device is flat and may be carried in the waist-device is flat and may be carried in the waist- 30 coat pocket. It is always in good condition as a fresh blade may be inserted easily and quickly. Moreover, it can be opened with one hand without using the finger nails for this purpose as is the case with an ordinary penknife, and it provides means of 35 utilizing safety razor blades which may possibly be otherwise thrown away or discarded as waste.

I claim:—

40 1. A device for enabling safety razor blades to be used for various other purposes besides shaving, comprising in combination, a handle portion formed of two flat strips of material connected together at their ends so as to leave a space between them, a blade holder connected to one end of said handle portion and formed of two flat strips of metal arranged side by side and connected together at their ends so as to 45 form a wedge shaped slot between them, a safety razor blade in said slot, and means for clamping the sides of the blade holder to grip said blade in any adjusted position therein.

55 2. A device for enabling safety razor blades to be used for various other purposes besides shaving, comprising in combination, a handle portion formed of two flat strips of material connected together at their ends 60 so as to leave a space between them, comb-like teeth formed along one edge of one of

said strips, a cut away portion along the edge of the other strip registered with said comb-like teeth, a blade holder connected to one end of said handle portion and formed of two flat metal strips arranged side by side and connected together at their ends so as to leave a wedge shaped slot between them, a safety razor blade freely mounted within said wedge shaped slot, and means for clamping 70 the two sides of said blade holder together to grip said blade in any adjusted position therein.

3. A device for enabling safety razor blades to be used for various other purposes 75 besides shaving, comprising in combination, a handle portion formed of two flat strips of material connected together at their ends so as to leave a space between them, a blade holder connected to one end of said handle portion by means of a pivot, said blade holder being formed of two strips of metal arranged side by side so as to form a wedge shaped slot between them, said wedge shaped slot being closed at one end, a slot or recess 80 in one edge of each strip constituting the blade holder and located intermediate their ends, a safety razor blade mounted freely in said wedge shaped slot, and means for clamping the strips forming the sides of 85 the blade holder together so as to grip the blade in any adjusted position.

4. A device for enabling safety razor blades to be used for various other purposes besides shaving, comprising in combination, a handle portion formed of two flat strips of metal connected together at their ends so as to leave a narrow space open on each side, between them, a blade holder 90 formed of two flat strips of metal connected together at their ends so as to form a wedge shaped slot between them open on each side, said blade holder being connected to one end of said handle portion by a pivot so as to enable the blade holder to be moved with 95 relation to the handle portion in the manner of an ordinary pen knife, a safety razor blade adapted to be inserted in either the wedge shaped slot in the blade holder or in the space between the strips constituting the 100 handle portion. Screw clamping means on said blade holder for drawing the strips constituting the sides thereof together to grip the blade when inserted therein, and screw clamping means on said handle portion adapted to clamp the strips thereof together to grip the blade when inserted in 110 the space therebetween.

ERNEST NORBERT KENNEDY.
